CUTTING AND FOLDING MACHINE

Alfred Laukhuff, Milwaukee, Wis.

Application August 20, 1941, Serial No. 407,567

21 Claims.

(Cl. 270—61)

This invention relates to an improvement in cutting and folding machines for webs of materials, and while particularly adapted for cutting and folding textile material, such as gauze, for example, in fabricating surgical sponges, it may also well be utilized for cutting and folding paper and various other materials for diverse other purposes.

An object of the invention is to provide a machine of this character, which is compact and 10 closely organized in construction, which is continuous and rapid in operation, which is comparatively inexpensive to manufacture, and which may be operated to advantage at a low maintenance and operating cost.

Another object of the invention is to provide a machine having these characteristics and advantages, and wherein the web of material to be cut and folded moves at a constant speed, starting and stopping being eliminated, and this with 20 high operating efficiency so that there is no waste, and at the same time a neat, sanitary, folded article is had.

In the operation of the machine, the web of material is cut clean and straight and is folded 25 along definite and permanent lines so that the resulting article has the dimensions and form required for its intended purpose or use.

Other objects and advantages reside in certain novel features of the construction, arrangement, and combination of parts, which will be hereinafter more fully described and particularly pointed out in the appended claims, reference being had to the accompanying drawings forming a part of this specification, and in which:

Figure 1 is a diagrammatic view in elevation showing the general form of machine embodying the present invention;

Figure 2 is a diagrammatic view partly in elevation and partly in transverse vertical cross section, illustrating the rotary drum embodied in the machine of the present invention, together with the folders with which it is equipped and the operating mechanism for the blades of the folders;

Figure 3 is a view partly in transverse horizontal cross section and partly in top plan, illustrating the cutting mechanism embodied in the machine, its operating devices, and certain of the operating cams for the blades of the folders;

Figure 4 is a fragmentary view in end elevation looking toward the lower end of Figure 3;

Figure 5 is a view in top plan of one of the folders provided on the periphery of the rotary drum and some of the operating mechanism for the folding blades thereof;

Figure 6 is a fragmentary view similar to Figure 5 and showing the manner in which the take-off blade coacts with one of the folding blades to remove a folded article from a folder;

Figure 7 is a fragmentary diagrammatic view partly in side elevation and partly in vertical cross section, further illustrating the operation of taking off folded material from the folders of the drum;

Figure 7a is a diagrammatic view showing the manner in which the gauze is folded, the showing being enlarged and exaggerated for the sake of illustration;

Figure 8 is a fragmentary diagrammatic view 15 similar to Figure 2 but showing a severed length of material on a folder after the first folding operation and with the outer folder blades returned to material-receiving position;

Figure 9 is a view similar to Figure 8 but illustrating the manner in which the final folding operation is accomplished;

Figure 10 is a fragmentary perspective view further illustrating the mechanism employed for oscillating the cutter shaft;

Figure 11 is a diagrammatic view partly in end elevation and partly in vertical cross section, showing one of the hold-down devices cooperable with the folders;

Figure 12 is a plan view of the hold-down member proper of the hold-down device shown in Figure 11;

Figure 13 is a view similar to Figure 12 of the second hold-down device employed in connection with the final folding operation; and

Figure 14 is a view in transverse horizontal cross section taken on line 14—14 of Figure 13.

Referring to the drawings, and more particularly to Figure 1, it will be seen that a machine embodying the present invention includes a suitable main frame, designated generally at M. An extension M' of the main frame supports a roll R of the material to be cut and folded. As indicated, the machine is adapted to operate on various kinds of material, such as knitted or woven textile material, paper, or the like, but for the sake of example or illustration it will be described as suitable for use upon woven fabric of the type known as gauze and which when appropriately folded may be used as surgical sponges. A web W is led from the roll R over a guide roller G, and thence past pressure rollers P and P' to a rotary drum, designated generally at D.

On the periphery of the drum there is provided 55 a plurality of angularly spaced folders, desig-

nated generally at F. These folders are of identical construction and they and their supporting structure constitute the periphery of the drum. The web W of the fabric is fed on to the periphery of the drum D and against the folders F; and the pressure rollers P and P' engage angularly spaced portions of the web W which is laid against the drum D to press the material against the folders F and stretch it thereon.

Cutting mechanism, designated generally at C, is combined with the drum and functions generally to sever predetermined lengths of the web after it has passed the pressure rollers and while it is on the folders. The drum D is supported for rotation about the shaft S as an axis. Means is provided for continuously rotating the drum and includes an electric motor E supported on the main frame M and acting through chain and sprocket gearing, the trains of which are designated at G, G', and G'', to drive the drum D at an appropriate speed.

Cutter actuating cams, designated at A and A' (see Figure 1) are driven from the gear train between the motor E and the drum and act through linkage, designated generally at L and L', to impart the appropriate movement to the cutting mechanism C, as will be hereinafter more fully described. The rotary motion of the drum D is utilized to actuate the operating mechanism for the folders F, as will be hereinafter more fully described.

The shaft S is supported adjacent its ends in suitable bearings 10, one of which is shown in Figure 10, these bearings being carried by the frame of the machine. The drum D comprises spaced hubs 11 having webs 12 suitably flanged and appropriately interconnected with the circular end plates 14 of the drum.

The folders F are supported on the end plates 14 of the drum. Each folder F includes four folding blades, designated at 15, 16, 17, and 18 (see Figures 2 and 5). The folding blades are of identical construction and each comprises a strip-like body portion 19 from one edge of which project a plurality of spaced parallel folding fingers 20. The outer folding blades 15 and 18 are provided at their ends with brackets 21 and 22. Journals 23 are fixedly secured to the brackets 21 and are rotatably supported on bearing pins 24 fixed to and projecting inwardly from the adjacent end plate 14 of the drum. The brackets 22 are provided with openings in which integral sleeve-like extensions 25 of pinions 26 are press-fitted or otherwise suitably secured. The pinions 26 have central openings aligned with the openings of their sleeves. Bearing pins 27, mounted on the end plate 14 of the drum adjacent the pinions 26, project into the openings of the pinions 26 and provide the support on which the pinions 26, and consequently the adjacent ends of their folding blades, are rotatably mounted. The folding blade 16 is also provided at its ends with brackets 28 and 29, similar to the brackets 21 and 22. Bracket 29 is provided with a journal 30 rotatably supported on a fixed bearing pin or stud 31 carried by the adjacent end plate 14 of the drum. The bracket 28 has an opening therein in which an integral sleeve-like extension or hub 32 of a pinion 33 is secured. A shaft 34 is rotatably supported in a bearing 35 provided therefor in the drum (see Figure 6), and its inner end extends through the axial opening in the pinion 33 and projects therebeyond, and its inner extremity is extended into an opening in a bracket 36 of the folding

blade 17 and is pinned thereto, as at 37, so that the shaft 34 supports the adjacent end of the folding blade 17 and also has driving connection therewith. The opposite end of the blade 17 is provided with a bracket 38 having a pin 39 fixed thereto and projecting into a bearing opening provided therefor in the bracket 29 of the blade 16.

When the folding blades 15, 16, 17, and 18 are in position to receive material to be folded, they rest on suitable supports provided therefor on the drum. In the embodiment of the invention illustrated, these supports are constituted by inwardly facing channels 40 extending transversely of the drum at spaced angular intervals thereabout and having their ends secured by angle brackets 41 to inner drum plates 42, these inner drum plates 42 being fastened by bolts, nuts, and spacer sleeves, or other suitable fastening devices 43 to the end plates 14 of the drum. On each of the channels 40 is a row of fabric-supporting pads 45, these pads being of rectangular form and being positioned and dimensioned to be received within the spaces between adjacent folding fingers 20 of the folding blade which engages the channel 40 on which the pads 45 are provided so as to supplement the action of the folding blades in providing a substantially continuous supporting structure or surface for the material laid against each folder. Both the folding blades and the pads 45 may be faced with felt, or other material adapted to have appropriate frictional engagement with the gauze.

As will be seen to advantage in Figures 1 and 2, there is a space 46 between adjacent folders F. The present invention proposes to have the cutting mechanism C sever the web of material extending across each space 46 at a certain period in the revolution of the drum. To adapt the cutting mechanism for that purpose, and for efficient action in other respects, it is constituted of a pair of cutters or knives, one designated at 50 being disposed on the outside of the periphery of the drum D, and the other, designated at 51, being located inside the drum. The cutters or knives 50 and 51 are supported for radial movement with respect to the drum so that the cutters may be brought into and out of cutting engagement at the periphery of the drum and in the spaces 46 between the adjacent folders F. The cutters or knives 50 and 51 are also supported for swinging or oscillating movement about the axis of rotation of the drum, namely about the axis of oscillation of the shaft S, and they are so actuated that in certain phases of their operation they swing in the same direction and at the same speed as the drum, while in alignment with a space 46, and when so swinging and so aligned are moved toward each other and into cooperative cutting engagement to sever a predetermined length of the web while it is on one of the folders. While swinging in the same direction as the drum, the cutters or knives 50 and 51, after the completion of the cut, are moved away from each other and are then thereafter reversely swung to reposition them for the next cut. In carrying out these purposes, the cutter 50 is bolted or otherwise suitably secured to the transverse angle bar 52 of an outer cutter frame, designated generally at 53. The bar 52 is longer than the drum is wide and is attached at its outer ends to the side bars 54 of the cutter frame 53. These side bars 54 are supported for rectilinear sliding movement in oscillating guides, designated generally

at 55. There is one such oscillating guide at each end of the machine, but only one is shown complete in Figure 3. However, as they are identical, it is believed that the illustration of one will serve. Each guide 55 includes a cylindrical hub 56 keyed to the outer end of a sleeve shaft 57 supported for rotation on and with respect to the shaft S by means of suitable bearings, one of which is designated at 58. Integral with the outer end of each hub 56 is an elongated frame plate 59 of generally rectangular form. Guide rollers 60 are provided at the corners of this plate 59 and the side bars 54 of the outer cutter frame have guiding engagement with these rollers 60. These rollers 60 are only diagrammatically illustrated, but preferably they are a suitable type of anti-frictional roller. For moving the outer cutter knife 50 in and out, each side bar 54 of its frame has a rack 61 fixed thereto, the teeth of each rack 61 meshing with the teeth of a cooperable pinion 62 fixed to the adjacent portion of the shaft S.

The inner cutter or knife 51 is also bolted or otherwise suitably secured to a transverse bar 63 of an inner cutter frame, designated generally at 65. This inner cutter frame is located entirely within the drum and its bar 63 is fastened in a suitable manner to the side bars 66 of the inner cutter frame. The side bars 66 are interfitted with the guide rollers 67 of the inner cutter frame, the guide rollers 67 being four in number for each side bar 66 and being supported on hubs 69 which are keyed to the inner ends of the sleeve shafts 57. By interconnecting the inner and outer cutter frames in this manner through the sleeve shafts 57, they are constrained to corresponding oscillatory movement so that their movements are synchronized in this respect. To move the inner cutter or knife 51 in and out, racks 70 are fastened to the side bar 66 of its frame and are meshed with pinions 71 fixed to adjacent portions of the shaft S.

As previously indicated, the cutter mechanism C is actuated by the cams A and A' through linkage L and L'. The linkage L includes a connecting rod 75 which has its upper end pivotally connected to one of the frame plates 59 of the outer cutter frame and its lower end pivotally connected to one end of a cam follower lever 76, the opposite end of the lever 76 being pivoted to a fixed fulcrum 77, and an intermediate portion thereof having a follower roller 78 riding on the cam A.

The linkage L', actuated by cam A' for oscillating the shaft S to move the cutters 50 and 51 toward and away from each other, includes a follower roller 79 provided at the end of one arm of a bell crank 80 and riding on cam A'. The lever 80 is fulcrumed at its elbow on the fulcrum 77 and has its upper arm connected to one end of a connecting rod 81 which is operatively connected to a rack 82 suitably guided and meshing with a pinion 83 fixed to the shaft S.

After the cutting mechanism C has functioned to sever a length of fabric from the web W, the folder on which said severed length of fabric lies is actuated to fold it. The folding operation is a four-stage one. First, the outer folding blades 15 and 18 are swung from their material-receiving position, wherein they rest against their channels 40 into a position wherein they overlie the folding blades 16 and 17, as illustrated in the upper left-hand corner of Figure 2. This folds the end portions or sections a and b of the severed length of material on the folder along the

lines a' and b' and, in so doing, folds them back on to the portions c and d of this severed length of material which portions c and d lie against the folding blades 16 and 17 in the manner illustrated in Figure 8. The second stage of the folding operation involves returning or swinging back the folding blades 15 and 18 from their material-folding position illustrated in the upper left-hand corner of Figure 2 to their material-receiving position shown in Figures 5 and 8. During this return movement of the folding blades 15 and 18 sections a and b of the material are held folded against return movement with the folding blades 15 and 18 by means of a hold-down device, designated generally at H, and which will be hereinafter more fully described. The third stage of the folding operation involves the swinging of the folding blade 16 from the material-receiving position, shown in Figure 8, over to a material-folding position shown in Figure 9, in which position the folding blade 16 overlies the blade 17 and folds the material along line c' so that the sections a and c now overlie sections b and d. In the fourth stage of the folding operation, the folding blade 16 is returned or swung back from the material-folding position, shown in Figure 9, to the material-receiving position shown in Figures 2, 5, and 7. For a portion of this return movement of the folding blade 16, the folding blade 17 moves with it, or more specifically the folding blade 17 moves from its material-receiving position, shown in Figures 8 and 9, to a take-off position shown in Figure 7, in which take-off position the folding blade 17 projects outwardly from the drum, as shown in Figure 7. After the blade 17 reaches the position shown in Figure 7, the blade 16 continues to move until it is in its material-receiving position. As the blade 16 moves away from the blade 17 and the folded material thereon to its material-receiving position shown in Figure 7, the folded material is restrained from movement with the blade 16, and is held in position on the blade 17, by means of a hold-down device, designated generally at H', as shown in Figures 13 and 14, and hereinafter more fully described. When the blade 17 is projected as described with the folded material thereon, it travels past a take-off blade 85 (see Figures 6 and 7). The take-off blade 85 is similar in construction to the folding blade 17 in that it has a strip-like body portion 86 from one edge of which take-off fingers 87 project. These take-off fingers 87 are dimensioned, proportioned, and positioned to pass between the folding fingers of the blade 17 so that as the blade 17 passes the take-off blade 85 the folded material is automatically transferred to the take-off blade 85. Suitable operating mechanism, illustrated diagrammatically at 88, is provided for automatically operating the take-off blade 85.

In order to automatically operate the folders F in the manner described, a separate operating mechanism, designated generally at O, is provided for each folder. As these operating mechanisms are of identical construction, a single description will serve for all of them.

Each operating mechanism comprises a pair of gear segments 90 and 91 pivotally supported, as at 92 on the end plate 14 of the drum adjacent the pinions 26 and having their teeth in mesh with the tooth of the pinions 26. The gear segments 90 and 91 are constrained to corresponding movement by virtue of the provision on each of an integral lever arm 100, the lever arms extending

toward each other and having intermeshing gear segments 101 at their adjacent ends. The lever arms 100 and their intermeshing gear segments 101 constrain the gear segments 90 and 91 to corresponding movement. The pivot shaft 91', to which the gear segment 91 is fixed, is extended outwardly beyond the bearings 12a provided therefor in the adjacent end plate 14 of the drum, the adjacent web 12 and the sprocket wheel G of the chain and sprocket gear G fixed to these parts (see Figure 3), and to the projecting outer end of this shaft 91' a follower lever 102 is fixed. The outer end of each follower lever 102 is provided with a follower roller 103 which rides against the periphery of a fixed cam 104 mounted on the frame of the machine. As the drum D rotates, the follower rollers 103 of the operating mechanism O of each folder F ride against and around the periphery of the fixed cam 104, and consequently the rollers 103 of each operating mechanism O move in and out as the contour of the cam 104 varies, with the result that its follower lever 102 is swung to oscillate shaft 91' and cause segment 91 and its intermeshed segment 90 to rock or oscillate, thereby oscillating the pinions 25 and appropriately actuating the folder blades 15 and 18 of each folder F at the proper time.

The operating mechanism for the folder blade 16 of each folder F also includes a gear segment 105 supported for pivotal movement at the opposite end of the drum from the segments 90 and 91. Each gear segment 105 meshes with pinion 33 of its folder F. Each gear segment 105 is fixed to the inner end of a pivot shaft 105 supported for rotation in bearings 12b provided therefor on the drum D. The outer end of each pivot shaft 105 has a follower lever or arm 106 fixed thereto. A follower roller 107 is carried by each lever or arm 106 and rides on a fixed cam 108. Here, again, as the drum rotates it carries each segment 105, its follower arm 106, and its roller 107 with it so that, during one period in each revolution of the drum D, each segment 105 is rocked to oscillate its pinion 33 and appropriately swing its folding blade 16.

The operating mechanism also includes means for shifting the blade 17 to take-off position, said means comprising a crank arm 112 fixed to the outer end of shaft 34 and provided with a roller 113 cooperatively engageable with a fixed cam 115 mounted on the frame of the machine and functioning to oscillate the shaft 34 so as to appropriately swing the blade 17 at the proper time.

The hold-down mechanism for preventing unfolding of the fabric upon return movement of the folding blades 15 and 18 is shown to advantage in Figures 11 and 12, and comprises a hold-down member, designated generally at 116, constructed of light spring metal having a central strip-like body portion 117 with springy hold-down fingers 118 projecting from the opposite edges thereof. The hold-down fingers 118 are designed to fit in between the folding fingers of the folding blades 15 and 18 to press the gauze against the underlying pads 45 carried by the channels 48 underlying the folding blades 16 and 17 as the folding blades 15 and 18 swing back from their folding position shown in the upper left-hand corner of Figure 2 to their material-receiving position shown in Figures 5 and 8.

To accomplish their purposes, the hold-down member 116 is moved toward and away from the drum D to cause their fingers 118 to engage the

folded gauze of each folder F at the proper time and for the proper interval, and when and while the fingers 118 press against the folded gauze on any folder F, these fingers, and of course the hold-down member 116 on which they are formed, move in the same direction and at the same speed as the drum D.

Suitable mechanism is provided for operating the hold-down member 116 in the manner described.

As illustrated in Figures 11 and 12, the hold-down member 116 may have its body portion 117 provided at each end with apertured hanger brackets 120. Pivotal connections 121 and 122 coact with these hanger brackets 120 to suspend the hold-down member 116 from the outer ends of floating links 123, one at each end of the hold-down member. A spring 122 may be incorporated in the pivotal connection 122 to frictionally or yieldably maintain the hold-down member 116 in proper position. The rearward ends of the floating links 123 are pivotally interconnected with a cross shaft 124. Adjacent its ends the cross shaft 124 is pivotally supported in bearings 125 provided therefor at the upper ends of rock arms 126. The rock arms 126 have their lower ends fixed to and supported on a rock shaft 127 supported for rocking movement in stationary bearings provided therefor in the frame of the machine. In this way, when the shaft 127 is rocked both rock levers 126 are rocked and both floating links 123 are moved back and forth. One of the lever arms 126 has a second lever arm 128 integral therewith. The upper end of connecting rod 129 is pivotally connected to the outer end of the second lever arm 128. The lower end of this connecting arm 129 is pivotally connected to one end of a follower lever 130. The opposite end of the follower lever 130 is pivotally supported on a fixed fulcrum shaft 131. A follower roller 132 is rotatably supported on an intermediate portion of the lever 130 and rides on an actuating cam 133 fixed to and rotatable with a cam shaft 134 driven in synchronism with the other elements of the machine. The cam 133 acts through the roller 132, connecting rod 129, lever arm 128, rock shaft 127, and rock arms 126, to move the floating links 123 back and forth in such manner that at the proper time the hold-down member 116 carried by the floating links is moved in the same direction and at the same speed as the drum D to adapt it to be moved down to engage the gauze in the manner described. For moving the floating links up and down so as to move the hold-down member 116 into and out of engagement with the folded gauze, the floating links 123 are suspended by double links 135 from rock arms 136 pinned to a rock shaft 137 supported for rocking movement in suitable bearings on the machine frame. One of the rock arms 136 is pivotally connected to the upper end of a connecting rod 138, the lower end of which is pivotally connected to a bell crank follower 139 pivotally supported on the fulcrum shafts 131 and having a follower roller 140 riding on a cam 141 fixed to the cam shaft 134. The cams 133 and 134 are so designed as to coordinate movement imparted to the hold-down member 116 to cause it to function in the manner described.

A similar structure designated generally at H' is also incorporated in the machine for preventing unfolding of the material when the folding blade 16 moves away from the folding blade 17

after the final folding operation. This latter instrumentality H' is shown in Figures 13 and 14 and includes a hold-down member or presser foot 150 constructed of light spring metal and having a strip-like body portion 151 from one longitudinal edge of which hold-down fingers 152 project. The hold-down fingers 152 are dimensioned, proportioned, and designed to pass between the folding fingers 20 of the folding blade 16 and lightly engage the folded material to prevent it from following the folding blade 16 as the latter moves away from the folding blade 17, thereby retaining the folded material on the blade 17. The action is appropriately light though highly effective. For actuating the hold-down member 150 with a properly timed though rapid light up and down movement, the body portion 151 of the hold-down member is suitably connected to the lower ends of hanger strips 153 pivotally supported at their upper ends on oscillating levers 154. The levers 154 are pinned to a rock shaft 155 supported in suitable bearings 156 carried by the frame M of the machine. Links 157 parallel to the levers 154 aid in constraining the hanger strips 153 to proper movement, these links 157 being fulcrumed as at 158 on the machine and being pivotally or otherwise appropriately connected as at 159 to the strips 153. A connecting rod 160 has its upper end pivotally connected as at 161 to one of the levers 154. The lower end of the connecting rod is pivotally connected to the outer end of a follower lever 162, the opposite end of the lever 162 being fulcrumed as at 163 on the frame of the machine. Intermediate its ends the lever 162 is provided with a follower roller 164 which rides on a cam 165 driven by a cam shaft 166. The shaft 166 is driven in properly timed relation to the other elements in the machine and the cam is so contoured as to impart the proper movement at the proper times to the vibrating hold-down member or presser foot 150.

The rotary drum D equipped with a plurality of angularly spaced folders F, constructed and arranged in the manner described, presents a drum periphery in the form of a polygon circumscribed by the circular edges of the end plates of the drum D, and it is this general structure of the drum which requires the provision of the pressure rollers P and P' to press the material against the blades of the folders F and stretch it thereon. In order that these pressure rollers P—P' may best serve their purpose, they are mounted for rotation on the outer ends of levers 170, one at each end of each rollers. At one side of the machine at least each lever 170 is provided with an integral lever arm 171, the lever arms 171 extending toward each other. The lever arms 171 are pivotally connected to the upper ends of slide rods 172, intermediate portions of which slidably extend through guide openings provided therefor in an adjustable abutment 173. The lower end of each slide rod is provided with an adjustable abutment in the form of a nut 174. A compression coil spring 175 is interposed between each nut 174 and the adjustable abutment 173. The springs 175 apply yielding pressure on the slide rods 172 which act through the lever arms 171 and the levers 170 to urge the rollers P and P' with the yielding pressure against the periphery of the drum. By having the abutment 173 adjustable, the threading or reeving of the web W through the machine and starting is facilitated. Preferably the abutment 173 is in the form of a bell crank lever having one arm appro-

priately connected to one end of the connecting rod 176. The opposite end of the connecting rod 176 is pivotally connected to a hand lever 177 which may be releasably secured in position to suitably compress the springs 175 by means of a latch 178. When the latch 178 is released the hand lever may be swung to relieve the compression on the springs 175 and allow the rollers P and P' to drop away from the periphery of the drum.

From the foregoing it will be understood that a machine of the character described is continuous in operation in that the web to be cut or folded moves at constant speed; starting and stopping are eliminated; high operating efficiency with no waste is had; and a neat, sanitary, folded article is economically produced at a very rapid rate.

While I have shown and described one construction in which the invention may be advantageously embodied, it is to be understood that the construction shown has been selected merely for the purpose of illustration or example, and that various changes in the size, shape, and arrangement of the parts may be made without departing from the spirit of the invention or the scope of the subjoined claims.

I claim:

1. A cutting and folding machine of the character described comprising a rotary drum having a plurality of folders disposed at spaced angular intervals about the periphery of the drum, means for continuously rotating the drum, means for supplying a web of material to the periphery of the drum, pressure rollers engageable with angularly spaced portions of the web of material disposed about the periphery of the drum for pressing the material against the folders and stretching it thereon, cutting mechanism for severing a predetermined length of the web after it has passed the pressure rollers and while it is on one of the folders, and means for thereafter actuating said last-named folder to fold said severed predetermined length of the web.
2. A cutting and folding machine of the character described comprising a rotary drum having a plurality of folders disposed at spaced angular intervals about the periphery of the drum, means for continuously rotating the drum, means for supplying a web of material to the periphery of the drum and against the folders thereof, cutting mechanism operating in the spaces between adjacent folders for severing a predetermined length of the web after it has been applied to one of the folders, and means for actuating each folder after it has a severed length of the web thereon.
3. A cutting and folding machine of the character described comprising a rotary drum having a plurality of folders disposed at spaced angular intervals about the periphery of the drum, means for continuously rotating the drum, means for supplying a web of material to the periphery of the drum and against the folders thereof, cutting mechanism operating in the spaces between adjacent folders for severing a predetermined length of the web after it has been applied to one of the folders, means for actuating each folder after it has a severed length of the web thereon, and means for taking the folded severed lengths of the web from the folders.
4. A cutting and folding machine of the character described comprising a rotary drum having a plurality of angularly spaced folders about

its periphery, means for supplying a web of material to the periphery of the drum and against the folders thereof, cutting mechanism for successively severing predetermined lengths from the web after they are placed on the folders, and means for successively actuating the folders which have a severed length of the web thereon.

5. A cutting and folding machine of the character described comprising a rotary drum, a folder thereon, means for feeding a web of material to the folder, cutting mechanism for severing a length of material from the web after it has been placed against the folder, and means for actuating the folder when the severed length of material is engaged therewith.

6. A cutting and folding machine of the character described comprising a rotary drum, a folder thereon, means for feeding a web of material to the folder, cutting mechanism for severing a length of material from the web after it has been placed against the folder, means for actuating the folder when the severed length of material is engaged therewith, and means for taking the folded material from the folder.

7. A cutting and folding machine of the character described comprising a rotary drum having a plurality of folders disposed at spaced angular intervals about the periphery of the drum, means for continuously rotating the drum, means for supplying a web of material to the periphery of the drum and against the folders thereof, means engaged with angularly spaced portions of the web disposed about the periphery of the drum for pressing the material against the folders and stretching it thereon, a pair of cutters one disposed inside and the other disposed outside of the periphery of the drum, means supporting said cutters for transverse movement with respect to the drum so that the cutters may be brought into and out of cutting engagement at the periphery of the drum and also supporting the cutters for swinging movement about the axis of rotation of the drum, means for swinging the cutters in the same direction and at the same speed as the drum while in alinement with the space between adjacent folders thereof and also for reversely swinging the cutters to re-position them for the next cut, means for moving the cutters toward each other and into cooperative cutting engagement as they are swung in the same direction and at the same speed as the drum to sever a predetermined length of the web while it is on one of the folders and also for moving the cutters away from each other before they are reversely swung for re-positioning, and means for successively actuating each folder after it has a severed length of the web thereon.

8. A cutting and folding machine of the character described comprising a rotary drum having a plurality of folders disposed at spaced angular intervals about the periphery of the drum, means for supplying a web of material to the periphery of the drum and against the folders thereof, a pair of cutters one disposed inside and the other disposed outside of the periphery of the drum, means supporting said cutters for transverse movement with respect to the drum so that the cutters may be brought into and out of cutting engagement at the periphery of the drum, and also supporting the cutters for swinging movement about the axis of rotation of the drum, means for swinging the cutters in the same direction and at the same speed as the drum while in alinement with the space between adjacent

folders thereof and also for reversely swinging the cutters to re-position them for the next cut, means for moving the cutters toward each other and into cooperative cutting engagement as they are swung in the same direction and at the same speed as the drum to sever a predetermined length of the web while it is on one of the folders and also for moving the cutters away from each other before they are reversely swung for re-positioning, and means for actuating each folder after it has a severed length of the web thereon.

9. A folder of the character described comprising a rotary drum, a folder mounted thereon and including four similar folding blades disposed side by side and extending transversely of the periphery of the drum and supported for pivotal movement thereon, each folding blade including a strip-like body portion and a row of spaced folding fingers projecting laterally from one longitudinal edge of the strip-like body portion, supports on the drum against which the folding blades rest in the material-receiving position of the folding blades, means utilizing the motion of the drum for first moving the outer folding blades from the material-receiving to a material-folding position, wherein they overlie the intermediate folding blades, and for next returning the outer folding blades to their material-receiving position, means also actuated by the motion of the drum for swinging one of the intermediate folding blades from a material-receiving to a material-folding position to impart a final folding to the material on the folder and for returning said intermediate folding blade to its material-receiving position, and mechanism actuated by the rotary movement of the drum and connected to the other intermediate folding blade for moving it during the return movement of the first intermediate folding blade to a material take-off position.

10. A folder of the character described comprising at least a pair of folding blades, each folding blade having a strip-like body portion and a row of spaced folding fingers projecting laterally from one longitudinal edge of the body portion, supports against which the folding fingers rest in the material-receiving position of the blades, pads on the supports positioned between the folding fingers of the blades when the blades are in material-receiving position, means for swinging at least one of the blades from the material-receiving position to a material-folding position wherein it overlies the other of said pair of blades and for reversely swinging said blade to return it to material-receiving position, and a hold-down device having hold-down fingers adapted to be moved through the spaces between the folding fingers of the swinging folding blade and engageable with the folded material on the pads to retain the same folded during the return movement of the swinging folding blade.

11. A folder of the character described comprising at least a pair of pivoted folding blades, each including a strip-like body portion having a row of spaced folding fingers projecting laterally from one edge thereof, supports against which the folding blades rest in the material-receiving position thereof, means for swinging one of the folding blades from the material-receiving position to a material-folding position overlying the other folding blade and vice versa, and a hold-down device operable through the spaces between the folding fingers of the swinging blade and engageable with the folded material to retain it

folded during the return movement of said swinging blade.

12. A folder of the character described including a pivoted folding blade having a row of spaced folding fingers, means for swinging said blade from a material-receiving to a material-folding position and vice versa, and means operating through the spaces between the folding fingers to positively retain the material folded as said blade returns from material-folding to material-receiving position.

13. A folder of the character described including a pivoted folding blade having a row of spaced folding fingers, means for swinging said blade from a material-receiving to a material-folding position and vice versa, and a hold-down device having hold-down fingers projectible through the spaces between said fingers and engageable with the folded material to retain it folded as said blade returns from material-folding to material-receiving position.

14. A folder of the character described comprising a pair of folding blades, means for oscillating one of said blades to move it from a material-receiving to a material-folding position wherein it overlies the other of said blades and then back to material-receiving position, and means positively retaining the material folded on said other blade when said oscillating blade is moved from material-folding to material-receiving position.

15. A folder of the character described comprising a rotary drum, a folder thereon including a pivoted folding blade having a row of spaced folding fingers, means for swinging said blade from a material-receiving to a material-folding position, and vice versa, a hold-down device having hold-down fingers projectible through the spaces between said folding fingers and engageable with the folded material to retain it folded as said blade returns from said material-folding to material-receiving position, means for moving said hold-down device toward and away from the rotary drum, and means for moving said hold-down device in the same direction and at the same speed as the drum when the hold-down fingers are engaged with the folded material.

16. A folder of the character described comprising a rotary drum, a folder thereon including a pivoted folding blade having a row of spaced folding fingers, means for swinging said blade from a material-receiving to a material-folding position, and vice versa, and a vibrating hold-down device having hold-down fingers projectible through the spaces between said folding fingers and engageable with the folded material to retain it folded as said blade returns from material-folding to material-receiving position.

17. A cutting and folding machine of the character described comprising a rotary drum having a plurality of folders disposed at spaced angular intervals about the periphery of the drum, each of said folders including at least a pair of pivoted folding blades, the folding blades of the folders

constituting the periphery surface of the drum and presenting the general contour of a polygon, means for supplying a web of material to the periphery of the drum, yieldable pressure rollers engageable with angularly spaced portions of the web of material fed to the periphery of the drum for pressing the material against the folding blades and stretching it thereon, cutting mechanism for severing a predetermined length of the web after it has passed the pressure rollers and while it is on one of the folders, and means for actuating each folder after it has a severed length of the web thereon.

18. A folding machine of the character described including a rotary drum having a plurality of folders disposed at spaced angular intervals about the periphery of the drum, each of said folders including at least two pivoted folding blades, pinions on the blades, gear segments supported for pivotal movement on the drum and meshing with said pinions, a cam follower connected to said gear segments, and a cam fixed to the machine and cooperable with the followers to successively actuate the folders as the drum rotates.

19. A cutting and folding machine of the character described comprising a rotary drum having a plurality of folders disposed at spaced angular intervals about the periphery of the drum, means for continuously rotating the drum, means for supplying a web of material to the periphery of the drum against the folders thereof, cutting mechanism operating in the spaces between adjacent folders for severing a predetermined length of the web after it has been applied to one of the folders, cam means for actuating said cutting mechanism, and means utilizing the rotation of the drum for actuating each folder after it has a severed length of the web thereon.

20. A folding machine of the character described including a rotary drum, a folder thereon including a pivoted folding blade having a row of spaced folding fingers, means for swinging said blade from a material-receiving to a material-folding position, and vice versa, said blade in both of said positions lying within the confines of the drum, means for swinging said blade to a material take-off position where it projects laterally from the drum, a swingable take-off blade having a row of take-off fingers adapted to pass between the folding fingers of the folding blade and to take folded material therefrom when the folding blade projects from the drum in its material take-off position, and means for operating the take-off blade.

21. In a folder of the character described, an oscillating folding blade having material-engaging surfaces operative to adhere to the material to be folded and to fold the same, said blade having cut-outs between said material-engaging surfaces, and means operating through said cut-outs to retain the material folded.

ALFRED LAUKHUFF.
